UNITED STATES PATENT OFFICE

2,573,892

CONVERTIBLE DAVENPORT AND BED

Thomas F. Cooney, New Haven, Conn.

Application January 21, 1946, Serial No. 642,524

2 Claims. (Cl. 5—18)

1

This invention relates to an article of furniture which may be employed as a combined davenport and bed in that it may be used as a davenport when in folded position, may be unfolded to be used as a half-size bed, and may thereafter be extended to be used as a full-size bed.

In certain of its aspects the present invention relates to improvements in the operating unit for a combined davenport and bed shown in my prior Patent No. 2,328,260, granted August 31, 1943. In the device shown in this patent, and also in the present device, there is provided a main frame similar to that of the ordinary davenport in that there are provided a pair of end walls secured together adjacent the rear edges thereof so as to make a frame like that of the usual davenport. Between these end walls is mounted an auxiliary frame which may be moved forwardly to a position extended from the main frame, which frame carries a pair of superposed cushions or mattresses, one of which is pivoted to swing upwardly and outwardly to an extended position, and the other of which is mounted to be moved vertically while maintained in substantially parallel horizontal position.

The present invention is particularly concerned with the mechanism for holding the slideable frame in any position to which it may be extended and also concerns the provision of automatically extensible folding legs upon the swinging mattress or cushion, so that when the latter is swung outwardly to extended position the legs will automatically be extended to engage the floor, and when the cushion is swung in a reverse direction to folded position the legs will likewise be moved in a reverse direction and be folded against the side of the mattress in a concealed position.

One object of the invention is to provide a combined davenport and bed having an extensible auxiliary frame which may be slidably adjusted with respect to the main frame, and improved means for holding this unit in any adjusted or extended position.

A further object of the invention is to provide a combined davenport and bed having a cushion or mattress pivoted to swing upwardly and outwardly to an extended position, which cushion is provided with pivoted or folding supporting legs and mechanism for moving the supporting legs to an extended position automatically when the cushion is swung outwardly and restoring the supporting legs to their folded position when the cushion is swung inwardly.

2

A still further object of the invention is to provide a combined davenport and bed having an auxiliary frame slidably engaged with the main frame for extension therefrom, a cushion pivotally mounted in the unit, and resilient means for supporting the pivotal mounting of the cushion whereby the pivotal axis of the latter may yield vertically when subjected to weight.

To these and other ends the invention consists in the novel features and combinations of parts to be hereinafter described and claimed.

In the accompanying drawings:

Fig. 1 is a front elevational view of a combined davenport and bed embodying my invention;

Fig. 2 is a sectional view on line 2—2 of Fig. 1 showing the operating mechanism at one end of the davenport;

Fig. 3 is a sectional view on line 3—3 of Fig. 1 showing the parts in another position;

Fig. 4 is an elevational view with some parts in section showing the device, in full lines, in position for use as a half-size bed, and showing, in dotted lines, the extended position of the auxiliary frame;

Fig. 5 is an inside elevational view of one of the end sections or units of the auxiliary frame;

Fig. 6 is a sectional view on line 6—6 of Fig. 3;

Fig. 7 is a sectional view on line 7—7 of Fig. 3; and

Fig. 8 is a sectional view on line 8—8 of Fig. 3.

To illustrate a preferred embodiment of my invention, I have shown in Fig. 1 of the drawings a davenport having side frames 10 and 11, which side frames are connected by rods 13 and 14 and by the back frame 15. At their inner sides, the side frames 10 and 11 are recessed or cut away as at 18 and 19 to receive the sliding auxiliary frame to be hereinafter described.

This auxiliary frame comprises end sections connected by front and rear members 20 and 21. These end sections or units, one of which is shown at 22 in Fig. 5, are of like construction and are hollow and contain certain operating mechanism which will be hereinafter described.

The inner sides of the sections have secured thereto a plate 23 to cover the hollow portion or chamber which contains the operating mechanism.

Each of the end sections is provided with a roller 24 by which it is supported from the floor and which rollers enable it to move outwardly with the rollers in contact with the floor when moved, for example, from the full-line to the dotted-line position shown in Fig. 4. Also, the end sections may be provided with rollers 25 at

the rear edges thereof, which rollers operate in slots 26 in the side frames 10 and 11 of the main frame, so that the sliding or extensible unit will be properly supported at its rear end by the main frame in any position of adjustment.

Within each of the end frames 22 of the sliding unit is the operating mechanism for the lower of the two superposed cushions 27 and 28. This operating mechanism consists of a member 29 to the ends of which are pivoted links 30, the links being pivoted at 30a to the frames 22. Also pivoted to the ends of the member 29 are links 31 carrying upon their free ends pins 32 extending through arcuate slots 33 in the plate 23, which pins 32 carry the lower cushion 27 so that, when the links 30 and 31 at one end of the member 29 tend to straighten out, the cushion 27 will be raised from the position shown in Fig. 2 to that shown in Fig. 3. It will be noted that due to the arcuate shape of the slots 33 the cushion 27 is moved rearwardly during the beginning of its upward or raising movement and then again moved forwardly to lie in close juxtaposition to the cushion or mattress 28 when the parts are in the position shown in Fig. 4.

The mattress 28 is hinged or pivoted to the forward portion of each of the members 22 as shown in Figs. 2, 4 and 6. For this purpose a rod 35 extends through the mattress and projects from both ends thereof, this rod being rotatably mounted at its ends in blocks 36 supported in casings 37 in the end frames 22 upon compression springs 38. It will be noted that with this construction the mattress 28 may be swung through the dotted-line position shown in this figure to the full-line position shown in Fig. 4. In the latter position the parts are adapted to be employed as a half-size bed. It will be also understood that, as indicated in dotted lines in Fig. 4, the entire unit consisting of the frames 22 and both of the mattresses 27 and 28 may be slidably moved outwardly from the main frame of the davenport to make a full-size bed, as indicated in dotted lines in Fig. 4.

It will be noted that the pivot rod 35 is mounted half-way between the upper and lower surfaces of the mattress 28 so that when this mattress is swung outwardly to its extended position the reverse side thereof will be uppermost, but this uppermost side will be in the same plane as that occupied by the uppermost side of the mattress when it was in its folded position superposed upon the mattress 27. In order, however, for the upper surface of the mattress 27 and 28 to be at the same level in the extended position shown in Fig. 4 it is necessary to raise the mattress 27 when the mattress 28 is swung outwardly.

In order that this may be effected, a link 40 is pivoted at 41 to the mattress 28, this link being provided with a slot 42 to receive a pin 43 upon the upper end of a lever 44 pivoted at 45 in one of the end units 22, the lower end of this lever being pivotally connected to one end of a link 46, the other end of which is pivoted at 47 to the member 29. With this construction it will be apparent that when the mattress 28 is moved from its folded position to the dotted-line position shown in Fig. 2, the link 40 will be moved forwardly so that about the time the mattress reaches the vertical position shown in dotted lines in Fig. 2, the rear end of the slot 42 will have engaged the pin 43. This lost motion connection, permitting considerable movement of the mattress 28 before the lever 44 is moved, permits the mattress 28 to move out of the way of the

mattress 27 before the raising movement of the latter is begun. When the mattress 28 is moved from the dotted-line position in Fig. 2 to the position in Fig. 4, the lever 44 will also be moved about its pivot to move the member 29 to the left as shown in these figures and thereby raise the mattress 27 to the position shown in Fig. 4. The initial rearward movement of this lower mattress prevents it from striking against the mattress 28 until the latter has been moved outwardly to a sufficient extent to permit the forward movement of the mattress 27 as is effected by the upper ends of the slots 33. It will, therefore, be seen that to move the parts from the folded position shown in Fig. 2 to the position shown in Fig. 4 it is only necessary to swing the cushion 28 outwardly, and the cushion 27 will automatically be moved upwardly.

The mattress 28 is provided at each of its front corners with legs 49 pivoted to the mattress frame at 50. These legs occupy a folded position beside the mattress when the latter is in folded position and being extended when the mattress is swung to the position shown in Fig. 4. For this purpose a link 51 is pivoted at 52 to the leg 49, the other end of the link being curved downwardly and pivoted at 53 to the link 40 just rearwardly of the pivot 41. With this construction it will be seen that as the mattress member 28 moves from the position shown in Fig. 4 to the position shown in Fig. 2, the link 51 will be moved forwardly relatively to the pivot 50 so that the legs 49 will be moved in a counterclockwise direction and folded against the sides of the mattress. A reverse movement will, of course, take place when the mattress is moved from its folded position to the position shown in Fig. 4. Thus the legs 49 will be automatically extended and retracted.

When the sliding unit is moved outwardly or extended to its extended position with respect to the main frame, as shown in dotted lines in Fig. 4, it is desirable to provide means by which it may be locked in any desired extended position, and it is also desirable to lock this frame in its retracted position in order that it may not be accidentally extended or moved from its retracted position. For this purpose a frictional brake or stop member is provided in the form of a plunger 55, this plunger being mounted in one of the side frames 22 and extending upwardly therethrough to be provided with a flat head 56 adapted to engage the lower surface of the shoulder 57 at the upper edge of one of the recesses in the side frames 10 and 11. It will be understood that the side frames 22 with the operating mechanism therein, including the braking structure now described, will be repeated at each end of the frame. The plunger 55 is provided with a downwardly facing shoulder 57a below which is mounted a washer 58 against which washer bears a spring 59, which spring reacts upon the upper surface of an angle-shaped lever 60. The lower reduced end of the plunger 55 passes loosely through an opening in the end of the lever 60 and is provided below this lever with a nut or head 61 to secure the parts together. Acting downwardly on the washer 58 is a compression spring 62 of less strength than the spring 59, this lighter spring 62 tending to keep the plunger 55 in the depressed position shown in Fig. 8.

The lever 60 passes through a slotted casing 63 mounted in the end unit 22 and is pivotally supported in this casing upon a spring 64, the lever being provided with a depending lug 65 to be received within the spring. This arrangement

not only pivots this lever but also permits the pivot to move downwardly if necessary owing to the support of the lever upon the spring 64. Adjacent the outer ends of the lever are provided pins 66 and 67 projecting through slots 68 and 69 in one face of the unit 22, so that these pins may be engaged by the link 40 when the latter is in horizontal position as it is when the mattress frame 28 is in its folded position or in the extended position shown in Fig. 4. As illustrated in the latter figure, the lower surface of the link 40 will strike the pin 67 and depress the outer end of the lever 60, thus raising the plunger head 56 into engagement with the main frame of the structure and frictionally locking the auxiliary or sliding frame against movement. When the mattress frame 28 is in its folded position the lever 40 will engage the rear pin 66 and likewise lock the parts against movement.

The action of the spring 62 tends to keep the pins 66 and 67 at the upper ends of the slots in which they ride and also tends to maintain the plunger head 56 out of contact with the main davenport frame when there is no pressure upon the lever 60. Pressure upon the ends of this lever tends to compress the heavier spring 59 and acts to force the plunger head 56 upwardly. It does, however, permit movement of the inner end of the lever 60 relatively to the plunger after the plunger head strikes the main frame so as to provide for additional movement of the lever if necessary without further movement of the plunger. This lost motion connection between the parts allows for any inaccuracy that may exist in the manufacture or installation of the mechanism.

Springs 10 secured to the frame of one of the units 22 at their upper ends and at their lower ends to the member 29 assist in the movement of the member 29 in a direction to raise the cushion or mattress 27 and thus lessen the effort required to simultaneously swing the mattress 28 about its pivot and raise the mattress 27. It will also be understood that raising the mattress 28 about its pivot 35 whether from the position shown in Fig. 2 or from the position shown in Fig. 4 immediately disengages the member 40 from the pins 66 or 67, and thus relieves any pressure of the braking member 56 on the main frame so as to permit the auxiliary frame to be moved to extended position. In other words, if it is desired to extend the auxiliary frame from the position shown in full lines in Fig. 4, it is only necessary to slightly raise the mattress 28, thus relieving pressure of the member 40 on the pin 67 which will immediately free the brake and thus permit extension of the auxiliary frame.

While I have shown and described a preferred embodiment of my invention, it will be understood that it is not to be limited to all of the details shown, but is capable of modification and

variation within the spirit of the invention and within the scope of the claims.

What I claim is:

1. A davenport bed construction comprising a main frame having rigidly connected end sections, an auxiliary frame slidably connected to the main frame for retraction between said end sections and extension therefrom, a cushion member pivotally connected to said auxiliary frame to swing upwardly and outwardly therefrom, a braking member on said auxiliary frame adapted to frictionally engage one of said end sections, said member comprising a plunger movably mounted in the auxiliary frame, spring means urging said plunger out of engagement with said main frame, a lever pivoted on the auxiliary frame and having one end engaged with said plunger, a compression spring disposed between said end of the lever and a part of the plunger, and means engaging the lever on the side of the pivot opposite said end to compress said last-named spring and cause the braking member to engage the end section.
2. A davenport bed construction comprising a main frame having rigidly connected end sections, an auxiliary frame slidably connected to the main frame for retraction between said end sections and extension therefrom, a cushion member pivotally connected to said auxiliary frame to swing upwardly and outwardly therefrom, a braking member on said auxiliary frame adapted to frictionally engage one of said end sections, said member comprising a plunger movably mounted in the auxiliary frame, spring means urging said plunger out of engagement with said main frame, a lever pivoted on the auxiliary frame and having one end engaged with said plunger, a compression spring disposed between said end of the lever and a part of the plunger, a link pivoted to the cushion and having a pin and slot connection with the auxiliary frame, and said link engaging the other end of said lever when the cushion is swung outwardly.
